P. SCHAFER.
WINDOW FOR VEHICLE CURTAINS.
APPLICATION FILED NOV. 6, 1917.
1,279,451.

Patented Sept. 17, 1918.

UNITED STATES PATENT OFFICE.

PHILIPP SCHAFER, OF SEYMORE, INDIANA.

WINDOW FOR VEHICLE-CURTAINS.

1,279,451.

Specification of Letters Patent. Patented Sept. 17, 1918.

Application filed November 6, 1917. Serial No. 200,562.

To all whom it may concern:

Be it known that I, PHILIPP SCHAFER, a citizen of the United States, and a resident of Seymour, in the county of Jackson and State of Indiana, have invented a new and useful Improvement in Windows for Vehicle-Curtains, of which the following is a specification.

My present invention relates generally to the construction incident to the mounting of windows in apertures in the curtains of vehicles, particularly motor vehicles, my object being the provision of a construction of frame which will permit of ready change of the celluloid or other transparent material utilized, and also permit at the same time of a firm uniform connection with the curtains, without danger of tearing or otherwise mutilating the latter.

My invention therefore, resides generally in the construction as shown in the accompanying drawing, forming a part of this specification, and wherein:

Figure 1 is a view looking at the inside of the window.

Fig. 2 is a vertical section taken therethrough substantially on line 2—2 of Fig. 1.

Fig. 3 is an outer face view of the window, and

Fig. 4 is a detail perspective view of portions of the window in detached relation.

Referring now to these figures, my invention is directed to the windows mounted within flexible curtains of vehicles, particularly motor vehicles, portions of which are indicated at 10 in Figs. 1, 2, and 3, and resides in particular in connection with the mounting of transparent sections of material 11 within openings of the curtain 10 in such manner that this material, usually celluloid, may be removed whenever it is desired, or becomes necessary.

As will be presently made plain, my invention aims to support the transparent material 11 in place so that it may be readily removed and other material substituted, and in such manner as to normally hold the same firmly in place by means engaging the material of the curtain 10 around its opening in such way as to obviate danger of tearing or otherwise mutilating the curtain.

To accomplish the foregoing, my invention proposes a frame consisting of inner and outer abutting sections 12 and 13, each of generally rectangular form, although this

form may vary if, for instance, an oval or round window is desired.

The inner section 12 of the frame is curved in cross section and provided at certain points therewith apertures 14 to receive therethrough the extensions or prongs 15 of fastening members, the curved heads 16 of which as particularly seen in Fig. 4, are adapted to rest against the inner convexly curved surface of the frame section 12. These apertures 14 of the frame section 12 are in alinement with openings 17 through the transparent material 11 adjacent and around its outer edges and through a flexible strip 18 secured to the transparent section 12 around its edges, the latter together with those portions of the curtain 10 immediately adjacent its opening within which the frame is disposed, being clamped in use between the frame sections 12 and 13, as clearly seen in Fig. 2.

For this purpose the outer section 13 of the frame has an inner surrounding flange 19 opposite the inner edge of the section 12 so as to thus snugly engage the surface of the transparent material 11 around the inner portion of the frame to prevent ingress of water and moisture. The section 13 of the frame is also provided with an inwardly reverting flange 20 around its outer portion, serrated as plainly seen in Fig. 4, so as to provide a continuous series of teeth-like projections around the outer section, permitting the latter to firmly and uniformly clamp the adjacent portions of the curtain on the flexible strip 18 between the same and the outer portion of the curved inner frame section 12, as seen in Fig. 2, without however, entering the material of the curtain 10, so that I thus avoid danger of tearing and mutilating the latter.

The outer frame 13 is also provided with apertures 21 alined with the apertures 14 of the inner section 12, and with the apertures 17 before referred to and apertures in the adjacent portions of the curtain 10, to receive the prongs or extensions 15 of the fastening members 16, the extremities of which prongs or extensions are bent laterally upon the outer face of section 13, as clearly seen in Fig. 3, so as to removably lock the two sections of the frame in operative position.

It is thus obvious that my construction provides for securely clamping the window

frame with its transparent material, in connection with a flexible vehicle curtain, and to do this evenly and uniformly along a line around the frame and along a line of the 5 curtain outwardly beyond its perforations through which the removable fastening members of the frame normally extend.

I claim:

1. A window frame of the character described, including opposing sections between which to clamp a window covering, one of which is concavo-convex in cross section and the other of which has a flange around its inner edge and a serrated reverting flange 15 around its outer edge, both said flanges being extended toward the first section to respectively oppose the inner and outer edge portions of the concave face of said first section, and means to detachably connect the 20 said sections, extending through the same at spaced points therearound and between the inner and outer flanges of the last-named section.

2. A window frame of the character described, including opposing sections between which to clamp a window covering, one of which sections is concavo-convex in cross section and the other of which has a flange around its inner edge and a serrated reverting flange 20 around its outer edge, respec-

tively opposing the inner and outer edge portions of the concave face of the first section, and detachable fastening members extending through and connecting the said sections at points between the flanges of the 35 last-named section.

3. A window frame of the character described, comprising a pair of opposing frame sections adapted to clamp a window covering therebetween, including an outer frame 40 section having inturned flanges around its inner and outer edges, the outer flange of which reverts in an inward direction and is serrated and has an outer flat face, and an inner frame section having its inner edge 45 opposing the inner flange of the outer section and curved in cross section with its concave face toward the outer section and with its outer portion lapping and opposing the outer flat face of the reverting outer 50 flange of the outer section, and means extending through the outer frame section at points between its said flanges and through the inner frame section, for detachably uniting the sections, substantially as de- 55 scribed.

PHILIPP SCHAFER.

Witnesses.
